[57] CLAIM

The ornamental design for a combined easel and table,
substantially as shown.

DESCRIPTION

FIG. 1 is a perspective view of a combined easel and
table embodying my new design and shown in the posi-
tion for use as a table;

FIG. 2 is an end view of the combined easel and table as
seen from the front of FIG. 1;

FIG. 3 is a side view of the combined easel and table as
seen from the left side of FIG. 1;

FIG. 4 is a top view of the combined easel and table of
FIG. 1;

FIG. 5 is a bottom view of the combined easel and table
of FIG. 1; and

FIG. 6 is a perspective view of the combined easel and
table of FIG. 1 shown in the position for use as an easel.
